PERCUSSION TOOL

Edmund W. Roberts, Cincinnati, Ohio, assignor to Robert D. O'Connell and Joseph R. Sweeney, Cincinnati, Ohio, partners doing business as O'Connell & Sweeney

Application November 23, 1931, Serial No. 576,839

6 Claims. (Cl. 123—7)

My invention relates to that type of percussion tool or hammer in which a piston or plunger reciprocates axially in a cylinder, and strikes the end of a drill bit, chisel, tamper or other tool, at the end of its outward stroke; the plunger functioning as the piston of an explosion engine, and the blow being imparted by the force of an explosion effected upon the piston.

The internal combustion or explosion engine exemplified is of the two-cycle type, in which an explosion occurs at the beginning of each outward stroke of the piston.

It is the object of my invention to provide a new and improved percussion tool of simple character and rugged construction and having few parts compactly assembled; further, to provide novel means for imparting the outward stroke of the piston to the tool; and, further, to provide novel means for imparting forceful impact upon the tool.

It is the object of my invention, further, to provide novel means for actuating a fly-wheel by means of a piston and employing the inertia of motion of the fly-wheel for returning the piston during its compression stroke and freeing the fly-wheel connection from the piston at approximately the moment of actuation of the tool for imparting a forceful working stroke to the tool.

It is the object of my invention, further, to provide a novel arrangement of jacket space for the cylinder of an explosion engine, a fly-wheel, a magneto and a fan, the fan having communication with said jacket space which is open to the outside air, and so constructed and arranged in novel manner as to draw the air over the magneto.

My invention consists in novel parts, and in novel construction, arrangements and combinations of parts for accomplishing the objects stated.

My invention will be further readily understood from the following description and claims, and from the accompanying drawings.

In the drawings:

Fig. 1 is a sectional elevation through the axis of the piston and the cylinder taken along the line 1—1 of Fig. 2.

Fig. 2 is a sectional elevation taken along the line 2—2 of Fig. 1, with the exception that about two-thirds of the piston is not in section, and the crankpin is shown in less advanced position and as if cut off close to the crank arm.

Fig. 3 is an end view as seen from the left of Figs. 1 and 2, with the handles or grips removed.

Fig. 4 is a sectional elevation of the flywheel

casing taken along the line 4—4 of Fig. 1 with the flywheel not in section.

Fig. 5 is a diagrammatic view with the anvil block omitted, it being assumed that the piston acts directly on the tool-bit, and showing the piston, crank, roller and tool-bit in their relations at the end of the compression stroke.

Fig. 6 is a similar view of the parts, with the crank moved through an angle of forty-five degrees.

Fig. 7 is a similar view of the parts with the piston in its working stroke, and showing the outer end of the piston advanced beyond the broken line, which represents the limit of working stroke of a similar piston coupled journalwise with the crank.

Fig. 8 is a similar view of the parts, showing the piston at the end of its power stroke.

Fig. 9 is a similar view of the parts, showing their relations at the beginning of the return movement of the crank; and,

Fig. 10 is a similar view of the parts, showing the crank as having made an additional one-eighth revolution, prior to the parts again assuming the relations shown in Fig. 5.

In the drawings, the cylinder is indicated generally by the numeral 11. The cylinder has an outer or jacket wall 12, providing an annular space or jacket 13 between the cylinder and the jacket wall. At intervals in the jacket space 13 are ribs 14, integral with the cylinder and the jacket wall, providing longitudinal air spaces 15 comprising that portion of the jacket space contiguous to the left-hand end of the cylinder.

Bolted to the side of the cylinder uppermost in Fig. 1 is the by-pass plate or cover 15, providing a semi-annular space 16 corresponding to the by-pass or transfer port of the average two-cycle engine. Bolted to the side of the by-pass plate, and registering with the opening 17 provided in the plate, is the mixing valve 18. The tank 19 bolted to plate 15, provides fuel storage, and is connected with the gas valve of the mixing valve by a tube not shown in the figures.

Within the cylinder 11, and adapted to reciprocate axially therein, is the piston 20. The piston is provided with a longitudinal groove 21, in which is a guide roller 22, mounted on the threaded pin 23. The pin projects through the by-pass plate 15, and is threaded in the wall of cylinder 11. This guide roller or other suitable guiding means is advisable to prevent the piston from turning on its axis.

Mounted on the side of the cylinder 11, and held thereto by means of bolts 25, is the side

plate 24. In the side plate is journaled the crankshaft 26 within the ball bearings 27. The crankshaft comprises the crank arm 28 and the crankpin 29. The crankpin includes the roller 30 mounted on bearing rollers 31 on the rigid part of the crank pin.

In that side of piston 20 nearest the side plate 24 is provided a groove 32 of which the lower portion 32' is a running fit to roller 30. The upper portion is cut away, at the side nearest the cylinder head 53, at an angle of approximately 45°. The side of the piston is further cut away to provide the extensions 33 of groove 32 to clear crank arm 28.

15 The right-hand end of the piston is provided with a cup-shaped opening 20' to receive the extension 34' of the anvil block 34. The anvil block exemplified is shown as a supplemental or auxiliary piston provided with packing rings 20 for making the outer end of the cylinder airtight against leakage from the pre-compression chamber which is in the cylinder between the anvil block 34 and the piston 20. A similar opening 34'' is provided in the anvil block to receive 25 the end of the tool bit 36. The extreme right hand end of the anvil block is provided with an enlargement 35 registering with a correspondingly enlarged bore 35' in the end of cylinder 11. The piston is arranged to strike the anvil block, which transmits the impact to the tool-bit.

Lower cylinder head 37 is yieldingly attached to the cylinder through the medium of the springs 38, the bolts 39, and the hook nuts 40. Head 37 is provided with an opening suitable for the reception of the tool bit 36. Surrounding tool bit 36, and held loosely in one of the hook nuts 40, is a tool-retaining link 41, of a type frequently employed on air hammers to retain the tool bit when the hammer is lifted.

40 Mounted on the crankshaft 26, and fixed thereto, is the flywheel 42. Within the rim of the flywheel is mounted the ring-shaped magnet 43, which is one of the constituent parts of the flywheel magneto. In Fig. 4 are indicated the relative positions of the magneto coil 44, and the circuit breaker 45. In this figure they are shown as detached from the plate 46 (Fig. 1) to which they are fastened. Since the functioning of this type of magneto is well known in the art, further description thereof is unnecessary.

45 Integral with the flywheel are the fan blades 47, which serve to draw air through the cylinder jacket 13, and through the compartment surrounding the magneto, and to discharge the air to the atmosphere. In addition to the cooling air, exhaust gases, discharged from the cylinder through exhaust port X, enter the fan to be discharged therefrom.

To guard against over-heating the magnet 43, and thereby demagnetizing it, the magnet is mounted within the flywheel rim with its outer periphery in contact with ribs 47' extended from the blades 47. Thus are provided air spaces between the ribs, the inside of the flywheel rim, and the outer surface of the magnet, through which air may be drawn in addition to that circulating through the magneto compartment. Furthermore, less heat will pass by conduction from the flywheel rim to the magnet through the ribs than if the magnet were in contact with the entire inner surface of the rim.

70 Partially surrounding the flywheel 42 is an extension 24' of the side plate 24, comprising a hood to deflect the gases leaving the fan from striking the operator in the face. The lower

and the left hand portion of the extension 24' (Fig. 4) is open. Across the opening provided in extension 24' are guard bars 48 and 49.

80 In the wall of cylinder 11 are provided the ports C, I and X. Port C provides for ingress of the mixture from the mixing valve 18 into the space provided between the piston 20 and the anvil block 34. It also provides for egress of the mixture from the cylinder to the by-pass 16. Port I provides a passage for the mixture to enter the cylinder from the bypass. Port X provides a passage way for the egress of the exhaust gases from the cylinder to the flywheel fan, whence they are discharged to the atmosphere. The deflector 20'', integral with piston 20, bars the new mixture entering port I from passing directly across the end of the piston to port X, and deflects the mixture toward the head of the cylinder.

90 Bolted to plate 24 is the cover plate 50 provided with an opening 51 surrounding the crank-shaft nut 26', and providing a space between the nut and the plate for the insertion of a suitable starting crank. The same space further provides a passage way for air to enter the magneto compartment, the entering air passing through 95 openings 52 provided in the web of the flywheel.

Bolted to the left-hand end of the cylinder 11, is the cylinder head 53 in which is the spark plug 54. Attached to head 53 are ears 55 provided with internal screw threads for the reception of the handles 56. Covering the handles are the grips 57, preferably of rubber fabric, a heavy steam hose making a satisfactory grip.

100 In the operation of the invention, the machine is started in the same manner as any small explosion engine by spinning the flywheel with a suitable starting crank. The sequence of events of the cycle are those of any two-cycle explosion engine in which the mixture first enters the crank-case to be discharged therefrom into the 110 bypass with the difference that the functions of the enclosed crankcase are performed by the space provided between the end of piston 20 and anvil block 34. Since the functioning of a two-cycle engine is well known to the art, no detailed 120 description will be given.

115 The adaptation of the invention to the requirements of a percussion tool is shown in the diagrams Figs. 5 to 10. In these figures, the curved arrows signify the direction of rotation 125 of the crankshaft with the roller 30, designated by an unbroken circle. The crank arm 28 is designated by a broken line, and the path of the axis of the crankpin—the crank circle—by a dot and dash line. The straight arrows indicate the 130 direction of travel of the piston 20. The anvil block having been omitted, the tool bit 36 is shown in the position it would occupy if impacted directly by the end of the piston 20. The relative positions of the piston and the tool bit are 135 shown to the same scale in each of the figures.

In Fig. 5, the roller 30 has thrust piston 20 to the limit of the inner or compression stroke. It will be noted that the inner dead center position of the roller has not been reached, and that 140 further rotation of the crankshaft will not drive the piston further to the left, owing to the conformation of groove 32.

145 In Fig. 6 the crankshaft has turned through an angle of 45° after passing the inner dead center. The piston is shown as it would follow the roller when impelled by the force of an explosion in the cylinder, with the slanting side of the groove bearing against the roller. The crank-shaft is being driven by the piston, storing up 150

kinetic energy in the flywheel. It should be noted that the piston has made approximately a half of its normal stroke while the crankshaft has been making but one-fourth of the half revolution corresponding to the full stroke in one direction of the piston, the piston moving faster than the roller in the axial direction of the piston.

In Fig. 7, the crankshaft is shown as having made a quarter revolution corresponding to a half stroke of the piston, while the piston has made more than a normal full stroke to strike the end of the tool bit. The broken line near the right hand end of the piston indicates what would be a normal full stroke, that is, the position of that end of the piston had it been reciprocated by the crankshaft with the roller bearing against the right-hand side of the groove.

It should be noted that if the piston were reciprocated by the crankshaft through the medium of the roller in contact with the right-hand side of the cross groove in the piston, the piston would not come into contact with the end of the tool bit, or strike the anvil block 34 in the combination illustrated in Figs. 1 and 2. The axial distance between the broken line near the right-hand of the piston and that shown by the solid line in Fig. 7 represents the over-run of the piston at the instant of impact.

In Fig. 8, the crankshaft has made another one-eighth revolution, and the roller is 135° past the inner dead center position. The impact of the piston under the impelling force of the explosion has driven the tool slightly to the right of the position it normally occupies, as indicated in the previous figures, as shown by the greater distance between the dotted line and the end of the piston as compared with the interval indicated in Fig. 7. The roller is now out of contact with both sides 40 of the groove 32, and the axial movement of the piston is unrestrained by the roller. This freedom of restraint permits the piston to follow through and exert the full force of the explosive impulse upon the end of the tool bit, less only that 45 small proportion of this force required to keep the flywheel in movement and to compress the mixture in the right hand end of the cylinder.

In Fig. 9 the crankshaft is shown as having made slightly more than a full half turn and the piston has rebounded from the tool bit, to start on its return stroke. It should be noted that the right-hand side of groove 32 has not quite come into contact with roller 30.

In Fig. 10 the crankshaft has made a one-eighth revolution past the outer dead center position of Fig. 9. The roller has entered the lower half 32' of the groove 32, and the piston is now being impelled by the crankshaft from the energy stored in the flywheel to compress the explosive mixture in the explosion chamber at the left of the piston. This condition continues until the relative positions of the crankshaft and the piston are as in Fig. 5.

My improved device starts readily with the spark at the full advance required for best results at working speed, and throttle control and spark control may be omitted, thus materially simplifying the mechanism.

The apparatus has the peculiar faculty of operating more slowly when not crowded to the work than when the operator thrusts downward on the handles. For example, when the tool is lifted or when it is allowed to run by itself supported on a tamper, it will run at about 400 R. P. M. Crowded to the work it will speed up to

its normal working speed of 1100 R. P. M. or more.

In explanation of this it may be stated that in my improved device the return stroke of the piston is started by its rebound from the tool-bit. Furthermore, the stroke is slightly shorter when the tool is crowded. When idling, the force of the recoil is less, the distance through which the piston must rebound is longer, and the crankshaft has more work to do in picking up the piston to start it on the inward stroke. Hence, more of the energy stored in the flywheel must be expended to return the piston than when the rebound is more vigorous, as when the tool is crowded. The speed of the tool may in consequence be regulated by the pressure on the handles.

In my improved device, the widened portion of the cross-groove in the piston provides for the detachment of the piston from the rotating parts at the moment of impact, so that the major portion of the recoil is absorbed by the piston.

I claim:

1. In a percussion tool comprising an explosion engine as the motivating means, the combination with a cylinder, an explosion chamber at one end of said cylinder and a tool-bit at the other end of said cylinder, of a piston axially reciprocable in said cylinder, the piston having a groove provided therein within the cylindrical projection of the inner face of said cylinder and intermediate of the ends of said piston, the groove at a right angle to the axis of the piston and in one side thereof, said tool-bit slidably mounted at said other end of the cylinder, the piston operative to move the tool-bit, a crankshaft journaled on the cylinder and radial with relation to said piston, a flywheel on the crankshaft, a crankpin on the crankshaft, and a roller on the crankpin, the roller in the groove, a portion of the groove being a substantially running fit to the roller, another portion of the groove being wider than the diameter of the roller, the sides of said cylinder opposite the respective ends of said groove provided with recesses in which said roller is alternately received, and the wider portion of the groove so conformed that the piston may move faster than the roller when impelled by an explosion in the cylinder, and that the piston is free of restraint by the roller at the instant the piston strikes the tool-bit.

2. In a percussion tool, the combination of a cylinder, an explosion chamber at one end of said cylinder, a tool-bit slidably mounted at the other end of said cylinder, a piston axially reciprocable in said cylinder, said piston having a groove solely in one of its sides between its ends within the cylindrical projection of the inner face of said cylinder at substantial right angles to the axis of said piston and extending into said piston substantially to said axis, said piston operative to move said tool-bit, a crankshaft journaled on said cylinder radial with relation to said axis, a crank on said crankshaft located in said groove adjacent to said axis, and a flywheel on said crankshaft, the wall of said groove toward said explosion chamber having a slanting portion at one of its ends slanting outwardly toward said explosion chamber for widening said end of said groove and acting on said crank during explosion movement of said piston for rotating said crankshaft, said explosion movement being also the impelling stroke of said piston for impelling said tool-bit, the other end of the walls of said groove being substantially right-angular with relation to said axis, said crank having a substantially running fit with said other end of said walls for

returning said piston into said explosion chamber, the walls of said widened end of said groove so conformed that the piston may move faster in axial direction than the crank during such impelling stroke of said piston, and said piston being free of restraint by said crank at the instant of impact producing the cutting stroke of the tool-bit.

3. In a percussion tool, the combination of a cylinder, an explosion chamber at one end of said cylinder, a tool-bit slidably mounted at the other end of said cylinder, a piston axially reciprocable in said cylinder, said piston having a groove solely in one of its sides between its ends within the cylindrical projection of the inner face of said cylinder at substantial right angles to the axis of said piston and extending into said piston substantially to said axis, said piston operative to move said tool-bit, a crankshaft journaled on said cylinder radial with relation to said axis, a crankarm on said crankshaft, a crank on said crankarm located in said groove adjacent to said axis, and a flywheel on said crankshaft, the wall of said groove toward said explosion chamber having a slanting portion at one of its ends slanting outwardly toward said explosion chamber for widening said end of said groove and acting on said crank during explosion movement of said piston for rotating said crankshaft, said explosion movement being also the impelling stroke of said piston for impelling said tool-bit, the other end of the walls of said groove being substantially right-angular with relation to said axis, said crank having a substantially running fit with said other end of said walls for returning said piston into said explosion chamber, the walls of said widened end of said groove so conformed that the piston may move faster in axial direction than the crank during such impelling stroke of said piston, and said piston being free of restraint by said crank at the instant of impact producing the cutting stroke of the tool-bit.

4. In a percussion tool, the combination of a cylinder, an explosion chamber at one end of said cylinder, a tool-bit slidably mounted at the other end of said cylinder, a piston axially reciprocable in said cylinder, said piston having a groove solely in one of its sides between its ends within the cylindrical projection of the inner face of the cylinder at substantial right angles to the axis of said piston and extending into said piston substantially to said axis, said piston operative to move said tool-bit, a crankshaft journaled on said cylinder radial with relation to said axis, a crank on said crankshaft located in said groove adjacent to said axis, the sides of said cylinder in line with said groove provided with recesses between the ends of said piston in which said crank moves beyond the cylindrical projection

of said piston, and a flywheel on said crankshaft, the wall of said groove toward said explosion chamber having a slanting portion at one of its ends slanting outwardly toward said explosion chamber for widening said end of said groove and acting on said crank during explosion movement of said piston for rotating said crankshaft, said explosion movement being also the impelling stroke of said piston for impelling said tool-bit, the other end of the walls of said groove being substantially right-angular with relation to said axis, said crank having a substantially running fit with said other end of said walls for returning said piston into said explosion chamber, the walls of said widened end of said groove so conformed that the piston may move faster in axial direction than the crank during such impelling stroke of said piston, and said piston being free of restraint by said crank at the instant of impact producing the cutting stroke of the tool-bit.

5. In a percussion tool comprising an explosion engine, the combination of a cylinder, a piston reciprocable therein and arranged to operate a tool, a jacket-wall surrounding said cylinder, a jacket-space provided between said jacket-wall and said cylinder, said jacket-space having connection with the atmosphere, a crank-shaft for said piston journaled on said cylinder at right angles to the axis of said piston, a fly-wheel fixed to said crank-shaft, said fly-wheel located solely at one side of said piston, said fly-wheel provided with a fan-space, an air-conduit between said jacket-space and said fan-space, fan-blades in said fan-space fixed to said fly-wheel, and a magneto incorporated in said fly-wheel at the same side of said piston, and said fan-blades operative to draw air through said jacket-space and said conduit and over said magneto.

6. In a percussion tool comprising an explosive engine, the combination of a cylinder, a piston reciprocable therein and arranged to operate a tool, a jacket-wall surrounding said cylinder, a jacket-space provided between said jacket-wall and said cylinder, said jacket-space having connection with the atmosphere, a crank-shaft for said piston journaled on said cylinder at right angles to the axis of said piston, a fly-wheel fixed to said crank-shaft, a casing about said fly-wheel, said casing and said fly-wheel having a fan-space therein, said casing provided with an air outlet communicating with said fan-space, an air conduit between said jacket-space and said fan-space, said fly-wheel and said casing with said fan-space therein located solely at one side of said piston, fan-blades in said fan-space fixed to said fly-wheel, and a magneto incorporated in said fly-wheel at the same side of said piston and located in said fan-space, and said fan-blades operative to draw air through said jacket-space and through said air conduit over said magneto.
